SASH BALANCE

John A. Krish, Torrington, Conn.

Application September 14, 1938, Serial No. 229,965

2 Claims. (Cl. 292—75)

The present invention relates to a sash balance and has for its primary object to provide a device adapted to produce frictional engagement between the edges of the sash and the sash guide to 5 yieldably hold the sash in its adjusted position.

A further object is to provide a sash balance designed to eliminate the use of sash cords and weights, and which also prevents binding between the sash and the sash guide due to swelling or 10 from paint.

A further object is to provide a device of this character of simple and practical construction, which is efficient and reliable in use, neat and attractive in appearance, relatively inexpensive to 15 manufacture and otherwise well adapted for the purposes for which the same is intended.

Other objects and advantages reside in the details of construction and operation as more fully hereinafter described and claimed, reference being had to the accompanying drawing forming part hereof, wherein like numerals refer to like 20 parts throughout and in which—

Figure 1 is a fragmentary sectional view through a window frame and sash showing the 25 sash balance in position thereon.

Figure 2 is a fragmentary edge elevational view of the sash.

Figure 3 is a perspective view of the guide for the sash and

Figure 4 is a sectional view of a modified form 30 of mounting for the roller.

Referring now to the drawing in detail wherein for the purpose of illustration I have disclosed a preferred embodiment of invention the numeral 5 designates a window frame to the inner surface of which are secured the spaced guide strips 6 and 7. Also secured to the inner surface of the frame 5 is a metallic weather strip 8, preferably formed of a pair of duplicate sections as 35 shown in Fig. 3 of the drawing, each of said sections including an angular guide rib 9 adapted for positioning in the vertical channel 10 formed in the edge portion of the sash 11, one of said guide ribs being provided for the lower sash while the other of said ribs is provided for the upper sash. 40

One of the vertical edges of each of the weather strips 8 is also bent angularly as shown at 12 and cooperate to form the parting strip 13 between the respective sash.

The edge of the sash is also formed with a recess 14 adapted to accommodate a roller support 15, said roller support embodying wing portions 16 positioned in the channel 10 to prevent rotary movement of the roller support in the recess 14. The roller support also includes an opening 17, the edges of which are bent inwardly as shown at 18 to provide a mounting for the opposite ends of a pin 19 upon which a roller 20 is journaled. The roller is provided with flanges 10 21 adjacent its ends and between which the guide 9 is positioned, the roller being yieldably held in engagement with the guide by a coil spring 22 positioned in the recess 14 and bearing against the roller support to urge the same outwardly. 15

In the modified form of invention illustrated in Fig. 4 the roller support designated at 23 has one edge portion provided with a return bend as shown at 24 for engaging the end convolution 25 of the spring 26 to secure the spring to the roller 20 support.

It is believed the details of construction and manner of operation of the device will be readily understood from the foregoing without further detailed explanation. 25

What is claimed is:

1. A sash balance for a window sash wherein a guide is provided for the sash, said sash balance comprising a roller support adapted for mounting in the sash, said support being formed of 30 sheet metal and having portions struck inwardly in spaced parallelism, a roller rotatably supported on said inwardly struck portions and spring means engaging the support for yieldably urging the roller into engagement with the guide. 35

2. A sash balance for a window sash wherein a guide is provided for the sash, said sash balance comprising a roller support adapted for mounting in the sash, said support being formed of sheet metal and having portions struck inwardly 40 in spaced parallelism, a roller rotatably supported on said inwardly struck portion and spring means engaging the support for yieldably urging the roller into engagement with the guide, said support having an edge portion bent upon itself and 45 projecting between the convolutions of the spring to secure the spring to the support.

JOHN A. KRISH.
